AERIAL TOW ADVERTISER

Filed June 16, 1932

UNITED STATES PATENT OFFICE

BENJAMIN B. MOEUR, JR., OF TEMPE, ARIZONA

AERIAL TOW ADVERTISER

Application filed June 16, 1932. Serial No. 617,633.

This invention relates to improvements in aerial advertising devices and pertains particularly to a device designed to be towed through the air by an airplane.

- 5 The primary object of the present invention is to provide a novel aerial tow advertising device by means of which advertising may be displayed from the air in the form of words, symbols or figures and maintained 10 in the proper position at all times so as to be easily read or understood by persons upon the ground. The device may be employed also for exhibiting banners or other objects in the air and may be readily illuminated for 15 night exhibition as well as day.

Another object of the invention is to provide a novel aerial tow advertiser having novel means for connecting it with an airplane to facilitate its being drawn through 20 the air without shifting from a position in which it is best seen from the ground and also having novel means associated therewith whereby it may be readily released by the pilot of the airplane so that the plane will 25 not be endangered when landing by becoming entangled with the advertising matter.

A still further object of the invention is to provide an aerial tow advertiser of the above described character having means associated therewith whereby it may be released 30 in the air and carried down to the earth without injury, which feature is particularly desirable where the advertising structure may be of a character to become damaged if 35 landed with violence.

The invention will be best understood from a consideration of the following detailed description taken in connection with the accompanying drawing forming part of 40 this specification, with the understanding, however, that the invention is not confined to any strict conformity with the showing of the drawing but may be changed or modified so long as such changes or modifications mark 45 no material departure from the salient fea-

tures of the invention as expressed in the appended claims.

In the drawing:—

Figure 1 is a view of the structure embodying the present invention showing the same applied to the rear of an airplane;

Figure 2 is an enlarged detailed view of the mechanism by which the device is coupled with the airplane tail skid;

Figure 3 is an enlarged detailed view of the universal joint coupling between two elements of the device;

Figure 4 is a view showing a modified coupling connecting means between the unit of the device and the air vessel which comprises a parachute by which the device may be lowered.

Referring now more particularly to the drawing wherein like numerals of reference indicate corresponding parts throughout the several views, the numeral 1 indicates a conventionally illustrated rear end portion of an airplane showing the usual tail skid 2 thereof.

The device embodying the present invention is designed to be attached to the tail skid of the plane and to this end the skid is provided with a rearwardly extending hook 3.

One form of advertising arranged to be trailed through the air is indicated generally by the numeral 4. This matter which as shown comprises a series of letters 5 is suspended from a cable 6, the lower portions of the letters having weights 7 attached thereto so as to insure their being held in the proper upright position.

Each end of the cable 6 is connected with one of the two yoke members 8 of a universal joint which is indicated as a whole by the numeral 9 and the other one of these universal joint elements 8 is connected by a cable 10 with a release hook which is indicated generally by the numeral 11. This release hook 11 has a bill portion 12 which is pivotally attached as at 13 with the shank 14 and the

free end of the shank 14 is connected with the hook 3 which is carried by the tail skid 2. The end of the bill 12 of the release hook 11 is held in place by a release ring 15 which surrounds it and the adjacent portion of the shank 14 and which is designed to be pulled from this position by a cord 16 running to the cockpit of the plane, when the pilot of the plane desires to drop the material which he is trailing.

The other universal joint 9 which is at the trailing end of the structure being towed, has one unit 8 connected with the adjacent end of the cable 6 while the other unit thereof is connected by the cable 17 with a wind cone 18 of any suitable design. In addition to the main or top cable 6 there is provided an under cable 19 which connects the lower ends of the characters 5, which in the present showing are letters, and has its ends extended up and connected with the main cable 6 in the manner illustrated.

Where advertising matter of a breakable and expensive construction is employed it is desirable that the same be dropped from the plane, when the plane is preparing to alight, without damage and in order to accomplish this the forward tow cable 10 has substituted therefor the folded parachute 20 which is illustrated in Figure 4. The head end of this parachute is connected by a suitable short cable 21 with the bill portion of the release hook 11, while the suspension cords 22 of the parachute are connected with one of the elements 8 of the forward universal coupling or joint 9. From this it will be readily apparent that when the advertising matter is to be dropped by the plane, the parachute 20 will open up and thus lower the advertising matter gently to the ground.

While in the illustration of the present invention a number of letters have been shown suspended between the trailing or two cables 6 and 19, it is, of course, to be understood that the invention is not to be limited to such use for it will be apparent that there may be suspended in this manner banners, animal or human figures or other symbols besides the letters shown and it will also be apparent that the structure may be towed from an airship or dirigible as well as from an airplane.

The letters or other figures or characters being displayed may be painted any suitable colors to make them readably visible in the sky and when used at night they may be coated with a luminous paint or electrically lighted by direct connection with the electrical system of the airplane or by spot lights directed thereon from the ground. Where the structure is lighted from the electric system of the airplane it will, of course, be readily understood that electric bulbs will be mounted upon the trailing structure and it will be seen from this that the provision of the parachute as a part of the structure will

facilitate the dropping of the structure without damaging or destroying the same.

The release mechanism for the structure is provided so that when the driver of the plane wishes to land he can drop the structure and thus avoid the risk of becoming entangled therein on the landing field. The landing field crew can then gather up the dropped structure and have the field clear for the landing of the plane.

Having thus described the invention, what is claimed is:—

1. The combination with an airplane or other type of air vessel, of a body designed to be trailed from the air vessel, a cable for coupling one side of the body with the air vessel, a universal joint connection between the cable and the said body, means for coupling the other end of the cable with the air vessel, a universal joint connection at the other side of the body, and a hollow tubular stabilizing element connected with the second mentioned universal joint connection.

2. The combination with an airplane or other type of air vessel, of a body designed to be trailed from the air vessel, a cable for coupling one side of the body with the air vessel, a universal joint connection between the cable and the said body, means coupling the other end of the cable with the air vessel whereby the cable may be released from the vessel while the latter is in the air, a universal joint connection at the other side of the body, and a stabilizing device connected with the second mentioned universal joint for assisting in maintaining the body at a desired position in the air.

3. The combination with an airplane or other type of air vessel, of a body designed to be trailed through the air to be viewed from the ground, said body including a cable, a universal joint coupling at each end of said cable, a tow cable connected at one end with one of said couplings, means for detachably connecting the other end of said tow cable with the air vessel comprising a hook having a bill formed to be opened and means for normally maintaining the bill in closed position, means for effecting the opening of said hook bill while the air vessel is in flight, and a wind cone stabilizer connected with the other of said couplings.

4. The combination with an airplane or other type of air vessel, of a structure designed to be trailed from the vessel to be viewed from the ground, means for connecting one side of the structure with the air vessel comprising a folded parachute connected with the structure in such a manner as to facilitate its opening when the structure is dropped from the air vessel while in the air, and means for detachably connecting the parachute with the air vessel.

5. The combination with an airplane or other type of air vessel, of a structure de-

- signed to be trailed from the vessel to be viewed from the ground, means for connecting one side of the structure with the air vessel comprising a folded parachute connected with the structure in such a manner as to facilitate its opening when the structure is dropped from the air vessel while in the air, means for detachably connecting the parachute with the air vessel, and a wind controlled stabilizing member connected with the other side of the structure for assisting in maintaining the same in a desired position while being trailed through the air. 70
6. The combination with an airplane or other type of air vessel, of a structure designed to be trailed from the vessel to be viewed from the ground, comprising a cable, means for detachably coupling one end of the cable with the air vessel, a stabilizing element connected with the other end of the cable, a second cable having its ends connected with and adjacent the ends of the first cable and having its intermediate portion looping downwardly from the first cable when the device is in operation, and exhibition characters mounted between the first cable and the looped portion of the second cable, the said structure when in the air having the line of pull passing longitudinally through the first cable. 80
7. The combination with an airplane or other type of air vessel, of a structure designed to be trailed from the vessel to be viewed from the ground, comprising a cable, means for detachably coupling one end of the cable with the air vessel, a stabilizing element connected with the other end of the cable, a second cable having its ends connected with and adjacent the ends of the first cable and having its intermediate portion looping downwardly from the first cable when the device is in operation, exhibition characters mounted between the first cable and the looped portion of the second cable, the said structure when in the air having the line of pull passing longitudinally through the first cable, and weight elements carried by the second mentioned cable and disposed beneath the exhibition characters. 90
8. The combination with an airplane or other type of air vessel, of a structure designed to be trailed from the vessel to be viewed from the ground, comprising a cable, means for detachably coupling one end of the cable with the air vessel, a wind cone connected with the other end of the cable, a second cable having its ends connected with and adjacent the ends of the first cable and having its intermediate portion looping downwardly from the first cable when the device is in operation, exhibition characters mounted between the first cable and the looped portion of the second cable, the said structure when in the air having the line of pull passing longitudinally through the 100
